(57) **CLAIM**

I claim the ornamental design for the article square tissue box cover with dimpled edges, as shown and described.

DESCRIPTION

FIG. 1 is a perspective view of one embodiment of a square tissue box cover with dimpled edges having wood grain surface appearances and illustrating my new design;

FIG. 2 is a left-side elevational view thereof, it being understood that the undisclosed right-side elevational view is identical thereto;

FIG. 3 is a front elevational view thereof, it being understood that the undisclosed rear elevational view is identical thereto;

FIG. 4 is a top plan view thereof;

FIG. 5 is a bottom plan view thereof;

FIG. 6 is a perspective view of an alternative embodiment of a square tissue box cover with dimpled edges formed with smooth, plain surfaces and showing my new design;

FIG. 7 is a left-side elevational view thereof, it being understood that the undisclosed right-side elevational view is identical thereto;

FIG. 8 is a front elevational view thereof, it being understood that the undisclosed rear elevational view is identical thereto;

FIG. 9 is a top plan view thereof; and,

FIG. 10 is a bottom plan view thereof.
